REFRIGERATOR CAR DOOR FASTENER

Sven J. Strid, Chicago, Ill.

Application January 9, 1932. Serial No. 585,677

4 Claims. (Cl. 292—340)

This invention relates to door fasteners and more particularly to mechanism for holding a door or closure in a predetermined position.

One of the objects of the invention is the provision of new and improved door fasteners having a novel reversible keeper whereby the fastener may be associated with either edge of a door.

Another object of the invention is the provision of a novel door latch having a new and improved relative arrangement of the latch and keeper.

A further object of the invention is the provision of a new and improved door fastener that is provided with a novel arrangement of parts for permitting its operation by gravity.

A further object of the invention is the provision of a new and improved door latch having a novel arrangement for the attaching screws or other attaching means.

Another object of the invention is the provision of a new and improved latching mechanism that is simple in construction, inexpensive to manufacture, effective in use and that is strong and rugged in construction.

Other and further objects and advantages of the invention will appear from the following description taken in connection with the accompanying drawing, in which—

Fig. 1 is a plan view of the latching mechanism;

Fig. 2 is a side elevation showing the parts in engaging position;

Fig. 3 is a side elevation of a portion of a railway car showing the invention in position thereon;

Fig. 4 is a section on line 4—4 of Fig. 3; and

Fig. 5 is a fragmentary section of the keeper of the invention on a line perpendicular to the base of the keeper substantially midway between its edges.

For the purpose of illustration, the device is shown in connection with a railway car door, but it is understood that it may be used in other relations.

Referring now to the drawing, the reference character 10 designates a railway refrigerating car having the double doors 11 and 12 hinged at their outer edges, as at 13 and 14, respectively. The meeting edges of the doors may be complementarily beveled as shown at 15 and 16 in Fig. 4.

It will thus be seen that the latch and keeper may be attached for fastening either edge of the door, it being only necessary to invert the keeper to adapt it for use in connection with one edge or the other of the door.

It is thought from the foregoing taken in connection with the accompanying drawing that the construction and operation of the device will be apparent to those skilled in the art and that va-

rious changes in size, shape, proportion and details of construction may be made without departing from the spirit and scope of the appended claims.

In refrigerator cars, as commonly constructed at the present time, the doors are hinged and are adapted to swing outwardly. The A. R. A. rules require that in the interest of safety means be provided for securing the door while in open position. Usually this is accomplished by a latch and keeper mechanism mounted on the side wall of the car and on the free or swinging edge of the door.

Various devices have been employed for this purpose. Some are too complicated to be practical, others require accurate adjustment in their application, while still others are not sufficiently strong and rugged to endure the rough usage to which such devices are usually subjected.

The present invention seeks to remedy these defects by the provision of a latching mechanism, especially adapted for use on refrigerator railway cars and the like.

In the present invention the latching mechanism comprises a keeper 17 which is preferably, though not necessarily, attached to the side wall of the car and a latch mechanism which is secured to the free edge of the door.

The keeper 17 comprises a body portion 18 having a base or attaching flanges 19 provided with apertures 21a therethrough for receiving attaching screws or bolts.

The body 18 of the keeper is provided on what, for convenience of description, will be termed its upper face, with a recess 21a, and on its lower face with a similar recess 22. The two recesses are opposite each other and are separated by a web 23 which constitutes a reinforcing member for the body portion.

The web has an opening 22a through its forward portion for permitting the escape of water, dust and other foreign matter that may accumulate in the uppermost recess.

The front walls of the recesses constitute abutment members 20 and 30 for the latch, as will presently appear.

The latch mechanism comprises an attaching member 24 having flanges 25 by means of which the device is secured to its support.

The attaching member 24 is provided with a hinge lug 26 having a horizontal aperture 27 therethrough. A latch member 28 has one end bifurcated for attachment to the lug 26. The bifurcations 29 and 31 of the latch straddle the lug 26 and are pivoted to the lug by the pintle 32, as clearly shown in Figs. 1 and 2. The bifurcations 29 and 31 are each provided with a shoulder or abutment 33 which is adapted to engage the flange 25 for limiting the downward movement of the latch member 28. The free end of the latch

member 28 is provided with a catch 34 which is adapted to engage either the abutment member 20 or the abutment member 30 for holding the door, to which the latch is attached, in open position. The latch member has its nose or catch provided with an inclined surface 37 and the body portion of the keeper is provided with a cooperating inclined surface 38 and a similar inclined surface 39 on its free end whereby when the door is swung to its fully open position the latch member 28 will be caused to automatically engage one or the other of these shoulders or abutments 20 or 30, depending on which is uppermost.

15 When the inclined surface 37 of the latch 28 engages the inclined surface 38 in Fig. 2, the catch is elevated and falls by gravity behind the shoulder 20. A finger piece 41 which extends upwardly and forwardly from the body of the latch member adds to the weight of the latch so as to insure its operation by gravity. Furthermore, the shape of this finger piece renders it easy to grasp for releasing the latch and for closing the door. When the door is to be closed, it is only necessary to grasp the finger piece 41 and pull. The force of the pull not only releases the latch, but also moves the door toward closing position.

30 The shoulders 20 and 30 are considerably longer than the width of the catch, as shown in Fig. 1, whereby accuracy of attaching the parts is not necessary as ample tolerance is provided in this manner.

35 The length of the lug 24 is such that it is adapted to engage the outer flat end 42 of the body of the keeper 17 for limiting the movement of the door to which the latch member is applied. In this manner, any unnecessary shock on the latch member 28 is avoided when the door is thrown open violently, as is often done when the device is used on refrigerator cars. The free end of the keeper may be cored or have a portion removed as at 43 for decreasing the weight and the amount of metal used.

40 45 The side walls of the cars are commonly provided with projections that will not permit the doors when opened to be swung parallel therewith. The doors, when in fully opened position, will extend at an angle to the walls as shown in Fig. 4. It will thus be seen that the parts of the fastening means on the door will engage the part on the wall at an inclination, unless one part or the other is arranged at an inclination. Either the latch member or the keeper member, 50 or both, may be arranged at such an angle that the latch will be normal to the striker.

55 In the construction shown, the plane of the attaching flanges 19 are arranged at an acute angle to the axis of the body portion of the keeper, whereby the axis of the keeper and the latch will be in substantial alignment when the two are engaged.

60 The keeper being symmetrical is reversible, that is, it may by inversion be employed on either side of the door, thus avoiding the necessity of manufacturing them in rights and lefts. The latch being normal to its attaching flanges, it may be used on either edge of the door. This is considered an important feature of the invention since it makes provision for making the proper contact between the latch and its keeper without the necessity of manufacturing two sets of devices.

In Fig. 5 is shown a modified form of an attaching flange which may be used on either the keeper or the latch, or on both. This arrangement is especially advantageous where the wall or door is of comparatively thin material. When the supporting material is thin, the fastening means which are usually short screws will soon become loose under the severe usage to which the device is subjected and are easily pulled out.

10 In order to overcome this difficulty, provision is made for inserting the fastening means at an angle to the plane of the base or attaching flanges. As shown, the attaching flanges 19a of the keeper 17a have the openings 45 and 46 arranged at an angle to the plane of the flanges 19a so that when the attaching members, as the screws, are inserted they will be at an angle to the plane of the flanges. Preferably, though not necessarily, they converge inwardly whereby a pull outwardly on the keeper will cause 95 the attaching screws to clamp the material between them instead of pulling out.

15 In the operation of the device, when the doors are unfastened, they are swung to open position and the latch 28, which is held by the shoulder 33 from falling below a predetermined plane, rides up from the inclined plane 38 and falls automatically under the influence of gravity behind the shoulder 20.

20 What I claim, therefore, is:

1. In a door fastener, a keeper member comprising a body portion, attaching flanges on one end of said body portion, the plane of said flange being arranged at an angle to the axis body portion, said body portion being provided with 110 symmetrically arranged upper and lower recesses separated by a web having an opening in its forward position, the front walls of said recesses forming latch engaging shoulders.

2. In a door fastener, a keeper comprising a 115 body portion having similar recesses on opposite sides separated by a reinforcing partition, said partition having an opening in its outermost portion, the free end of said keeper having upper and lower inclined latch engaging surfaces converging forwardly and the forward walls of said recesses forming latch engaging shoulders and an attaching flange rigidly secured on the inner end of said body portion.

3. In a door fastener, a keeper comprising a 125 body portion having similar recesses on opposite sides separated by a reinforcing partition, said partition having an opening in its outermost portion, the free end of said keeper having upper and lower inclined latch engaging surfaces converging forwardly and the forward walls of said recesses forming latch engaging shoulders and an attaching flange rigidly secured on the inner end of said body portion, the axis of said body portion being arranged at an acute angle to the 135 plane of said flange, and said keeper being symmetrical whereby the same may be reversed.

4. In a door fastener, a keeper comprising a body portion, attaching flanges on one end of said body portion, the plane of said flanges being arranged at an angle to the axis of the body portion, the free end of said body portion having symmetrically arranged inclined surfaces converging outwardly, said free end having a latch engaging shoulder adjacent to each inclined surface inwardly thereof.

SVEN J. STRID.
